[57] CLAIM

The ornamental design for clip holder for wire or similar article, as shown and described.

DESCRIPTION

FIG. 1 is a front elevational view of a clip holder for wire or similar articles showing my new design; FIG. 2 is a rear elevational view thereof;

FIGS. 3 and 4 are respectively top and bottom plan views thereof;

FIG. 5 is a left side elevational view thereof, the side opposite being a mirror image thereof;

FIG. 6 is a left side, top and front perspective view thereof; and

FIG. 7 is a left side elevational view of a second embodiment thereof, the side opposite being a mirror image, the only difference between the two embodiments is that the first embodiment has a slight curvature of the back as shown in FIG. 5, and that the second embodiment has a straightback as shown in FIG. 7.

FIG. 1

FIG. 2

FIG. 3

FIG. 4

FIG. 5

FIG. 6

FIG. 7
